UNITED STATES PATENT OFFICE.

BERNHARD J. KROGH, OF CAMBRIDGE, WISCONSIN.

WATER-MOTOR.

1,215,386.

Specification of Letters Patent. Patented Feb. 13, 1917.

Application filed May 3, 1916. Serial No. 95,181.

To all whom it may concern:

Be it known that I, BERNHARD J. KROGH, a citizen of the United States, residing at Cambridge, in the county of Dane, State of Wisconsin, have invented a new and useful 5 Water-Motor; and I do hereby declare the following to be a full, clear, and exact description of the invention, such as will enable others skilled in the art to which it app pertains to make and use the same.

This invention relates to an improved wa ter motor, and an object of the invention is to provide a device of this kind, which is simple, efficient and practical in construction, 15 and may be constructed for a small cost, and sold at a reasonable profit.

Another object of the invention is the pro vision of a hydraulic movable drum mounted upon a thrust bearing of a supporting frame 20 and provided with inclined and curved blades arranged annularly, against which the water as it passes through the flume con tact, thereby imparting movement to the drum.

Another object of the invention is the pro vision of a plate engaging the upper surface 25 of the bottom of the flume and having a plu rality of openings annularly arranged, through which the water passes, to contact 30 with said blades, there being an improved valve plate having openings, to coöperate with the openings of the first plate, for con trolling the amount of water passing there through, so as to increase or decrease the 35 speed of the drum.

One of the features of the invention is the provision of a series of loosely suspended plates carried by the under surface of the valve plate for covering the openings of the 40 first plate, the loosely mounted plates act ing to accommodate themselves to the un evennesses of the upper face of the said first plate.

The practical fields the details of con struction may necessitate alterations falling 45 within the scope of what is claimed.

The invention comprises further features and combination of parts as hereinafter set forth shown in the drawings and claimed.

In the drawings:—

Figure 1 is a view partly in side eleva tion, partly broken away, and partly in sec tion, showing the improved water motor as applied to one end or the bottom of the flume.

Fig. 2 is a sectional view.

Fig. 3 is a top plan view.

Fig. 4 is a top plan view of the plate which is fastened to the upper face of the flume and bolted to the frame. 60

Fig. 5 is a top plan view of the drum, showing the upper end of the arm of said frame.

Fig. 6 is a plan view of the frame.

Fig. 7 is a detail perspective view of the 65 cover plate of the hydraulic movable drum, and the valve plate, illustrating the loosely suspended plate.

Referring more especially to the drawings 1 designates the bottom or one end of the 70 flume, upon one or the upper face of the portion 1 an annular plate 2 is arranged, and loosely fitting an opening 3 in the part 1 is the upper circumferential edge portion 75 of the hydraulically movable drum 4. This drum 4 comprises inner and outer annular walls 5 and 6, spaced apart from each other, thereby forming a channel. Connecting these walls 5 and 6 and arranged on angles and in the channel are blades 7 which are 80 curved as shown in Fig. 1. However, the upper portions of the blades 7 terminates a short distance below the upper edges of the walls 5 and 6. The upper and lower edges of the wall 5 are connected by the sheet 85 metal walls 8, and keyed centrally and ax ially in the walls 8, as shown at 9 is a verti cal shaft 10, the lower extremity of which is provided with a semi-spherical cavity 11, which receives or engages the semi-spherical 90 end 12 of a stud 13, rising from a block or member 14, which is held in place upon the frame 15 by a clamp 16. This clamp has a central cavity conforming to the shape of the block or member, so as to fit or receive 95 the same. A flange 17 rises upwardly from the frame 15, and threaded into the flange is a plurality of bolts 18, the inner ends of which bear against the clamp 16, and hold the same in place. It is to be seen 100 that by the provision of the thrust bearing, the hydraulically movable drum will rotate very freely, when the water which passes through the flume, contacts with the blades 7. The frame 15 is provided with a plural 105 ity of arms 19, having upstanding portions 20, which have reduced extremities 21, which pass through the bottom or one end 1 of the flume, and through the plate 2, there being nuts 22 engaging the upper surface of the 110 plate 2 and nuts 23 engaging the under sur face of the part 1, thereby not only holding

the frame 15 firmly in position, but also clamping the plate 2. The shaft 10 passes through a central opening of the plate 2, which is provided with a plurality of openings 24, arranged annularly coincident to the channel of the drum. Extending downwardly from the plate 2 is a pair of annular flanges 25 and 26, the inner flange 25 being adjacent the inner ends of the openings 24, while the flange 26 is adjacent the outer ends of the openings 24. Arranged between the flanges 25 and 26 radially of the plate 2 are water deflecting blades 27, which are inclined as to direct the water directly toward and upon the blades 7. In other words the blades 27 are inclined in a direction just the opposite to the inclination of the blade 7 so that as the water passes through the openings 24 will strike or contact with said blades 7 thereby imparting revoluble movement to the drum, which being keyed to the shaft 10, will impart motion to the shaft. Extending upwardly from the plate 2 is a pin 28, and arranged adjacent the upper part of the plate 2 is a valve plate 29, which is provided with a slot 30 through which the pin 28 extends, in order to limit the plate 29 in its movement, when being adjusted. The valve plate 29 is provided with a series of openings 31, and radial arms 32 alternately arranged, and the under face of the plate 29 adjacent the openings 31 and the arms 32 is recessed annularly, as is clearly shown in Fig. 2 and Fig. 7. This annular recess 33 of the under face of the plate 29 receives a plurality of auxiliary valve plates 34, the thicknesses of which are slightly greater than the depth of the recess 33, so that the auxiliary valve plates 34 will ride upon the upper face of the plate 2, so that in case the upper face of the plate 2 should be irregular, or should become irregular, the auxiliary valve plates will always slide evenly relative to their respective openings 24. This action is materially insured, owing to the auxiliary valve plates 34 being loosely suspended from the arms 32 by means of the studs or pins 37, which are elongated and pass through the openings 38 of said arms, there being riveted heads 39 at the upper ends of the pins or studs, to prevent disconnection of the auxiliary valve plates, when the dominant valve plate 29 is removed. Adjacent the edge of the dominant valve plate a short flange 40 is provided having gear teeth 41, which are engaged by the teeth of the pinion 42, which is carried by the lower end of a shaft 43. The lower end portion of the shaft 43 is mounted in a suitable bearing 44 in the frame of the flume so as to steady or hold the shaft in position. The shaft 10, may be extended to any suitable location and geared in any suitable manner (not shown) to machinery to be operated. The shaft 43 may be extended to

any suitable location and operated in any suitable manner, so that by rocking the shaft 43 in one direction or the other, the dominant valve plate may be adjusted, in order to control the flow of water through the co-operating opening. By moving the dominant valve plate 29 in one direction, the speed of the hydraulically movable drum may be increased, and by moving the dominant valve plate in the opposite direction, the speed of the drum may be decreased. 70 75

The invention having been set forth what is claimed as new and useful is:—

1. A submerged water turbine for flumes comprising a revoluble drum having annularly arranged inclined blades, said drum having thrust bearing, a frame for the support of said drum, a plate secured on said frame above the drum and provided with annularly arranged openings provided with plates inclined the opposite to the blades, and means for controlling the amount of fluid passing through said opening of said plate, said means comprising a valve carrying plate having a plurality of openings and the plurality of radial arms alternating with the openings of the valve plate. 80 85 90

2. A submerged water turbine for flumes comprising a revoluble drum having annularly arranged inclined blades, said drum having thrust bearing, a frame for the support of said drum, a plate secured on said frame above the drum and provided with annularly arranged openings provided with plates inclined the opposite to the blades, 95 and means for controlling the amount of fluid passing through said opening of said plate, said means comprising a valve carrying plate having a plurality of openings and the plurality of radial arms alternating with the openings of the valve plate, and the plurality of auxiliary valve plates loosely carried by said radial arms coöperating with the openings of the first plate for controlling the fluid therethrough. 100 105 110

3. A submerged water turbine for flumes comprising a revoluble drum having annularly arranged inclined blades, said drum having thrust bearing, a frame for the support of said drum, a plate secured on said frame above the drum and provided with annularly arranged openings provided with plates inclined the opposite to the blades, and means for controlling the amount of fluid passing through said opening of said plate, said means comprising a valve carrying plate having a plurality of openings and the plurality of radial arms alternating with the openings of the valve plate, and the plurality of auxiliary valve plates loosely carried by said radial arms coöperating with the openings of the first plate for controlling the fluid therethrough, and means for adjusting said valve plate. 115 120 125

4. A submerged water turbine for flumes 130

comprising a revoluble drum having annularly arranged inclined blades, said drum having thrust bearing, a frame for the support of said drum, a plate secured on said frame above the drum and provided with annularly arranged openings provided with plates inclined the opposite to the blades, and means for controlling the amount of fluid passing through said opening of said plate,
5 said means comprising a valve carrying plate having a plurality with the openings and the plurality of radial arms alternating with the openings of the valve plate, a plurality of auxiliary valve plates, the main
10 valve plate having annular recesses in its under face to receive said auxiliary valve
15

plates, said auxiliary valve plates having studs loosely mounted in said arms and designed to coöperate with the opening of the first plate to control the fluid through the 20 openings of the first plate, said main valve plate having a partial annular flange provided with gear teeth, and a rocking shaft having a pinion to engage said gear teeth for adjusting the valve plate. 25

In testimony whereof I have signed my name to this specification in the presence of two subscribing witnesses.

BERNHARD J. KROGH.
